US00D756527S

(12) **United States Design Patent**
Cole et al.

(10) **Patent No.:** **US D756,527 S**
(45) **Date of Patent:** **** May 17, 2016**

(54) **SKIN CLEARING AND TONING DEVICE**

(71) Applicant: **Carol Cole Company**, Vista, CA (US)

(72) Inventors: **Carol Cole**, San Marcos, CA (US); **Tera Peterson**, Carlsbad, CA (US)

(73) Assignee: **Carol Cole Company**, Vista, CA (US)

(**) Term: **15 Years**

(21) Appl. No.: **29/539,561**

(22) Filed: **Sep. 15, 2015**

Related U.S. Application Data

(63) Continuation of application No. 29/490,639, filed on May 12, 2014, now Pat. No. Des. 739,541.

(57) **CLAIM**

The ornamental design for skin clearing and toning device, as shown and described.

DESCRIPTION

FIG. 1 is a perspective view of the skin clearing and toning device of the present invention;

FIG. 2 is a front elevational view of the skin clearing and toning device shown in FIG. 1;

FIG. 3 is a rear elevational view of the skin clearing and toning device shown in FIG. 1;

FIG. 4 is a left side elevational view of the skin clearing and toning device shown in FIG. 1, the right side view being a mirror image of the illustrated view;

FIG. 5 is a top plan view of the skin clearing and toning device shown in FIG. 1; and,

FIG. 6 is a bottom plan view of the skin clearing and toning device shown in FIG. 1.

The broken lines in the Figures show portions of the skin clearing and toning device which form no part of the claimed design.

1 Claim, 3 Drawing Sheets
